J. DENEMARK.
CIGARETTE CASE.
APPLICATION FILED JAN. 23, 1919.

1,305,699.

Patented June 3, 1919.

UNITED STATES PATENT OFFICE.

JACOB DENEMARK, OF TRENTON, NEW JERSEY.

CIGARETTE-CASE.

1,305,699.

Specification of Letters Patent. Patented June 3, 1919.

Application filed January 23, 1919. Serial No. 272,630.

To all whom it may concern:

Be it known that I, JACOB DENEMARK, a citizen of Russia, residing at Trenton, Mercer county, State of New Jersey, have 5 invented certain new and useful Improvements in Cigarette-Cases, of which the following is a full, clear, and exact description.

This invention relates to improvements in cigarette cases, the principal object being 10 to provide novel and efficient means to eject the cigarettes, one by one, from the case. To accomplish this result, I provide a rotatable receiver having an ejecting device, or more strictly speaking, means to raise the cigarette at one end thereof to facilitate the 15 grasping of the same. Other features of improvements will hereinafter appear.

I will now describe my invention in detail, and refer to the accompanying drawing, 20 wherein:—

Figure 1 is a top plan view of the case, the cover being removed;

Fig. 2 is an enlarged longitudinal sectional view thereof, certain parts being illustrated in elevation, the section being taken 25 on a line 2—2 in Fig. 1;

Fig. 3 is an enlarged cross sectional view, taken on line 3—3, Fig. 1, looking toward the right;

Fig. 4 is an enlarged fragmentary longitudinal sectional view of the cigarette receiver; and

Fig. 5 is an enlarged perspective view of the cigarette tilting arm.

My improved cigarette case comprises a suitable box 6 closed at one end 7 and open at the opposite end, as at 8, which I will term the ejecting end of the box. The box is provided with a cover 9 hinged as at 10 to a fixed cover-plate 11. The cover 9 carries a hasp 12 to be engaged by any suitable locking tongue, not shown in detail, but indicated by 13 in Fig. 1. Within the box I slidably mount a pusher 14 actuated by a spring 15 to force the cigarettes into the rotatable semi-cylindrical receiver 16, which carries trunnions 17 and 18 which are located eccentric to the axis of the receiver. The trunnions 17 and 18 are rotatably supported by the box 6, their points of bearing being concentric with the axis of the cylindrical end 8 of the box. To rotate the receiver, the trunnion 18 is provided with a thumb-wheel 19. One of the features of my invention is the tilting lever or arm 20, carried by the rotatable receiver 16, said arm

being formed to coincide with the shape of the receiver 16. Adjacent one end the lever or arm 20 is bent downwardly to pass through an opening 21 in the receiver 16, the outer end of the arm terminating in a pin 22 to engage a cam-slot 23 formed in a block 24 located at the adjacent end of the box 6. The arm 20 is pivoted, intermediate its ends to the receiver 16 by the pin 25. The cam-slot 23 is cut to provide a rise 26 to throw the arm or lever 20 outwardly, or in other words, to tilt same. The cam-slot 23 imparts positive movement to the receiver 16; in other words, acts to both open and close 70 the same. The rise 26 of the cam-slot 23 is juxtaposed relative to the opening at the end 8 of the case; hence the arm 20 will be tilted to the utmost when pin 22 reaches the apex of the rise of the cam. The tilting of 75 the arm 20 is greatly augmented by the eccentric movement of the carrier 16, which is timed so as to cause the receiver to move bodily toward the opening, at the end of the case, at about the time that pin 22 reaches 80 the ascent portion 27 of the cam-slot. The eccentric movement of the carrier, combined with the rise of the cam, causes arm 20 to be tilted or moved upon its pivot 25 sufficiently to force the adjacent end of the cigarette, 85 within the receiver, well out of the opening at the ejecting end of the box. To eject a cigarette the receiver 16 will be rotated. During the rotation of the receiver, a cigarette will be forced into the receiver by 90 pusher 14 and spring 15. At about the time that the cigarette alines with the opening, through which it is ejected, the receiver 16 and arm 20 will perform the operation above referred to.

Having described my invention, what I claim is:—

1. In a cigarette-case, a box-member open at one end, a rotatable receiver adjacent said opening, an ejecting arm pivotally connected to said receiver, and a cam-member carried by the box to operate said arm.

2. In a cigarette case, a box-member open at one end, a rotatable semi-cylindrical eccentrically mounted receiver adjacent said opening, an arm pivotally mounted within the receiver, and a cam to actuate said arm.

3. In a cigarette-case, a box-member, an ejector within same, means to rotate the ejector, and a cam to operate said ejector to force one end of a cigarette out of said box.

4. In a cigarette-case, a box-member open

at one end thereof, an eccentrically mounted rotatable ejector adjacent thereto, an arm pivotally connected, intermediate its ends, to said receiver, a portion of said arm projecting through an opening in said receiver, and a cam carried by the box engaging the end of said projecting portion of said arm and arranged to actuate said arm to force one

end of a cigarette out of the receiver when said receiver is rotated.

Signed at New York city, N. Y., this 21 day of January 1919.

JACOB DENEMARK.

Witnesses:

MAURICE BLOCK,

EDWARD A. JARVIS.
